UNITED STATES PATENT OFFICE

HOWARD P. ANDERSON, OF ERIE, PENNSYLVANIA, ASSIGNOR TO THE STANDARD STOKER COMPANY, INCORPORATED, A CORPORATION OF DELAWARE

LOCOMOTIVE TENDER

Application filed November 18, 1930. Serial No. 496,399.

This invention relates to improvements in locomotive tender construction particularly adapted to receive stoker mechanism.

It is an object of this invention to provide in a locomotive tender an L-shaped water tight compartment arranged to house a stoker fuel trough and a stoker engine at the rear of the trough and to permit access to the stoker engine through the tender sidewall.

10 Other objects and advantages of my invention will be apparent from the following description when taken in connection with the accompanying drawings, in which

Fig. 1 is a central longitudinal vertical section of the tender and stoker compartment with the stoker trough and engine diagrammatically shown therein;

Fig. 2 is a sectional plan view on the line 2-2 of Fig. 1;

20 Fig. 3 is a sectional view on the line 3-3 of Fig. 1; and

Fig. 4 is a sectional view on the line 4-4 of Fig. 1.

Referring to the drawings, the tender is represented generally at 10, and comprises the frame 11 and the tank 12 provided with the fuel compartment 13, the water compartment 14 and the stoker compartment 15. The tank used for purposes of describing the invention is shown as cylindrical but the invention is equally applicable to tanks of other shapes and designs.

The tank 12 comprises the base plate 16 to which sidewalls 17 and 18 are secured in a suitable manner as by riveting. The fuel and water compartments are separated by the side slope sheets 19 and 20 and the rear slope sheet 21.

The stoker compartment 15 formed in the water compartment 14 beneath the fuel compartment 13 is L-shaped and extends in a horizontal plane, with the long portion 22 of the L extending longitudinally of the tender, on its vertical central plane and opening 45 at the front end of the tender, and the short portion 23 of the L projecting laterally from the end of the long portion 22 opposite its open end and extending transversely of the sidewall 17 of the tender and opening there- 50 through through the aperture 23a.

The stoker compartment 15 is closed at its rearward end by the upstanding plate member 24 secured at its upper and its lower end to the rear slope sheet 21 and the tank base plate 16 respectively. The sidewalls of the 55 longitudinally extending portion 22 of the compartment 15 are preferably formed by the extensions 25 and 26 of the side slope sheets 19 and 20, and the floor is formed by the plate 27 secured along its opposite edges to the 60 extensions 25 and 26 and supported along its center from the tank base plate 16 by the support member 28. The roof of the portion 22 of the compartment 15 is defined by the floor 29 of the fuel compartment 13 and 65 the rear slope sheet 21.

The sidewall 25 of the portion 22 of the compartment 15 is apertured at its rearward end to permit communication with the laterally projecting portion 23 of the compartment 70 15. The portion 23 of the compartment 15 is closed at its rearward end by the upstanding plate member 24 and at its top, bottom and front by the walls 30, 31 and 32 respectively. The side of the portion 23 of the compartment 75 15 which projects through the tank sidewall 17 is provided with a hinged closure 33.

The floor 29 of the fuel compartment is carried from the sidewalls 25 and 26 in a suitable manner and is provided with a longitudinal central opening 34. Slide plates 35 are mounted in the opening 34 and may be moved from covering position to permit gravity feeding of fuel.

A fuel trough 36 is mounted in the stoker 85 compartment 15 beneath the floor 29 of the fuel compartment and is supported from the stoker compartment floor 27 by the plate-like supporting members 37. A screw 38 in the trough 36 receives fuel from the fuel compartment, advances it against a crusher 39 mounted in the forward end of the trough reducing it to a proper size for firing, from where the fuel is delivered by suitable conveying means to a firebox.

The drive for the screw 38 includes an engine or motor 40 mounted in the rearward portion of the stoker compartment 15. Motion is transmitted to the screw 38 from the engine 40 through reduction gearing 41 en- 100

closed in the gear casing 42. An oil drain 43 leads from the bed of the engine through a passage 44 connecting corresponding openings 45 and 46 in the stoker compartment floor 5 27 and the tank base plate 16 respectively. Steam for operating the engine 40 is supplied from the locomotive through the main steam line 47, and a control valve 48 regulates the flow of steam to the engine through the live 10 steam pipes 49 or 50 for operating the stoker forward or for reversing. The control valve 48 is provided with a stem 51 leading forwardly to a point convenient for the fireman for operating the valve in forward, neutral 15 or reverse positions. When the engine is being operated by live steam passing through the pipe 49, the exhaust from the engine passes through the pipe 50, and vice versa when the engine is being operated by live 20 steam passing through the pipe 50 then the exhaust from the engine passes through the pipe 49. The pipe 52 constitutes an exhaust to the atmosphere common to the pipes 49 and 50. An exhaust drip pipe is shown at 53. 25 The main steam line 47 is provided with the drain valve 54 and the discharge pipe 55.

The stoker drive mechanism is easily and conveniently accessible for purposes of inspection, repair or replacement from the side 30 of the tender through the laterally projecting portion 23 of the compartment 15. Locating the stoker engine at the rear of the conveyor screw instead of at the front of the tender or on the locomotive eliminates the 35 necessity of a drive shaft to the rear of the screw and the consequent loss of power. My improved tender construction permits of a compact, rugged, simple and easily accessible stoker and stoker drive mechanism.

40 I claim:

1. In combination in a locomotive tender having a base, a body portion with partition walls separating the fuel section from the water section thereof, and an L-shaped compartment, for housing stoker mechanism, lying in a horizontal plane formed in said water section beneath said fuel section, the long portion of said L-shaped compartment extending longitudinally of the tender on the 45 vertical central plane thereof and opening at the front end of the tender and the short portion of said L-shaped compartment directed laterally from the end of the long section opposite its open end and extending transversely of one side of the tender and opening 50 through the sidewall thereof.

2. In combination in a locomotive tender having a base, a body portion with partition walls separating the fuel section from the 55 water section thereof, and an L-shaped compartment, for housing stoker mechanism, lying in a horizontal plane formed in said water section beneath said fuel section, the long portion of said L-shaped compartment 60 extending longitudinally of the tender on the 65

vertical central plane thereof and opening at the front end of the tender and the short portion of said L-shaped compartment directed laterally from the end of the long section opposite its open end and extending transversely of one side of the tender and opening through the sidewall thereof, that part of said short portion within the walls of the tender being formed wholly within said water section.

3. In combination in a locomotive tender having a base, a body portion with partition walls separating the fuel section from the water section thereof, and an L-shaped compartment, for housing stoker mechanism, lying in a horizontal plane formed in said water section beneath said fuel section, the long portion of said L-shaped compartment extending longitudinally of the tender on the vertical central plane thereof and opening at the front end of the tender and the short portion of said L-shaped compartment directed laterally from the end of the long section opposite its open end and extending transversely of one side of the tender and opening through the sidewall thereof, said L-shaped compartment having vertical sidewalls each of which constitute a partition wall for said water section.

In testimony whereof I affix my signature. 95
HOWARD P. ANDERSON.
